UNITED STATES PATENT OFFICE.

ANTON E. NIELSEN, OF NEW YORK, N. Y., ASSIGNOR TO THE STERLING SUPPLY AND MANUFACTURING COMPANY, OF SAME PLACE.

FARE-REGISTER-OPERATING DEVICE.

SPECIFICATION forming part of Letters Patent No. 643,884, dated February 20, 1900.

Application filed July 19, 1899. Serial No. 724,376. (No model.)

To all whom it may concern:

Be it known that I, ANTON E. NIELSEN, a citizen of the United States of America, and a resident of the city of New York, borough 5 of Brooklyn, State of New York, have invented a new and useful Improvement in Fare-Register-Operating Devices, of which the following is a specification.

This invention relates to means for hanging "permanent" fare-registers of the type known as "double" registers in the passenger-cars of street and suburban railways or tramways and for transmitting the "ringing" or registering actuations to the same from the 15 customary or improved "ringing devices."

Heretofore double-register hanging-blocks or register-backs, with their appurtenances, of two more or less distinct patterns have been provided for use, respectively, in open 20 cars in connection with ringing devices extending lengthwise of the car at both sides and in closed cars in connection with a single ringing device lengthwise of the car.

The present invention consists in an improved register-back attachment or set of operating devices for double fare-registers convertible at will and in a moment for use either in open cars or in closed cars; also, in certain novel combinations of parts in such operating devices, as and for the purposes hereinafter set forth.

By "double" registers I mean those that are adapted to register and indicate two kinds of fares, as "transfers" and "cash fares."

The present operating devices are primarily intended for the Sterling Supply and Manufacturing Company's double fare-register described and claimed in a companion specification, forming part of my application for 35 patent filed simultaneously herewith the 19th day of July, 1899, and serially numbered 724,375. This improvement is, however, applicable to operating devices for double registers of other makes, and one and the same 40 pattern of the improved operating devices may be used in common for different registers of standard size.

A sheet of drawings accompanies this specification as part thereof.

50 Figure 1 of the drawings is a face view of

the improved double-register-operating devices, with a fragmentary edge view appended, as adapted for open cars, the same being shown in connection with a rod and strap handle ringing device. Fig. 2 is a face view 55 of the improved operating devices as adapted for closed cars, the same being shown in connection with a rod and plain handle ringing device; Figs. 3 and 4 are face views of the respective removable levers shown in Fig. 1, 60 with appended edge views; and Fig. 5 is a face view, with appended edge view, of the removable lever shown in Fig. 2.

Like letters and numbers refer to like parts in all the figures. 65

The improved double-register-operating devices comprise a cast-iron hanging-block or register-back A, Figs. 1 and 2, of peculiar construction having hasp and staple projections 1 and 2 at bottom and top, adapted to 70 coact, respectively, with the customary staple and hasp projections of double fare-registers, several of which are already of a standard size, so that one and the same pattern of register-back may be used in common. 75

The register-back A is preferably and conveniently dish-shaped, with countersunk screw-holes 3 in its sunken back to provide for fastening it in place within a car by wood-screws in customary manner, a pair of pivot-studs 4 and 5, one above the other, and a pair of stops 6 and 7 on said sunken back, a pair of notches 8 and 9 in the rim which supports the hasp and staple 1 and 2, and a flanged annular seat 10, interrupted by said notches 85 8 and 9, which is fitted to the back plate of the superposed register.

To coact with the customary actuator studs projecting through slots in the back plate of the register, a pair of main levers B and 90 B² are pivoted in common on said pivot-stud 4 and constructed with notches 11 in their outer ends, corresponding with said actuator stud-pins, and rigid arms 12 at top to coact with the ends of a spiral spring C, by which 95 said levers are normally held against said stops 6 and 7, as in Figs. 1 and 2. A pair of links D and D² are pivoted by pins 13 at their upper ends to said levers B and B², respectively, and are constructed with curved slots 100

14 in their relatively-thick lower ends. To coact with the slots 14 of said links D and D², a pair of removable levers E and E², Figs. 1, 3, and 4, or a single removable lever E', Figs. 5, 2 and 5, as the case may be, is pivoted on said pivot-stud 5. These removable levers are in common approximately T-shaped and constructed with stud-pins 15 on their lateral arms to coact with said slots 14 and with a stud-pin 16 at the other extremity of each to coact with the pivot-hole in a connecting-rod coupling 17 and with a split pin 18 or its equivalent for securing the connection. The stud-pin 5 and a pivot-boss 19 on each of the levers are adapted in like manner to receive and coact with split pins 20. In said arrangement (represented by Figs. 1, 3, and 4) the levers E and E² are coupled to a pair of connecting-rods F and F², Fig. 1, whose outer ends in common are coupled to lever-arms G, fastened by set-screws 21 on steel rods H, which are preferably and conveniently provided with cross-bar handle-levers I, fastened thereon at convenient intervals by set-screws 22 and provided with depending strap-handles J in pairs, the location of each handle thus indicating the registering mechanism thereby pulled. The peculiarly-curved shape of the levers E and E² in this arrangement 30 prevents any interference between the couplings 17 and permits the latter to be made as thick as may be required to coact with connecting-rods round in cross-section.

In the arrangement for closed cars (represented by Figs. 2 and 5) the single removable lever E' is coupled by a like connecting-rod F' to a like lever-arm G on a steel rod H at one side of the car provided with "plain" handles I—that is to say, rigid lever-handles—by each of which the rod H may be turned either way to actuate either registering mechanism and ring either bell of the double register through the medium of said lever-arm G, Fig. 2, connecting-rod F', removable lever E', link D or D², and main lever B or B². After each actuation the parts are restored to their normal positions by the single spring C, and the strain is in all cases, except at the plain handles I', a pulling strain, 50 producing a minimum of wear and tear.

The improved operating devices are readily and quickly adjusted for open or closed cars at the factory by substituting the levers E and E² for the lever E', or vice versa, or by 55 completing the partially-assembled devices in either form, as required.

Other fastening devices may be substituted for the split pins 18 and 20. The improved operating devices may be employed in connection with any known or improved construction of ringing device, and other like

modifications will suggest themselves to those skilled in the art.

Having thus described said improvement, I claim as my invention and desire to patent 65 under this specification—

1. Improved operating devices for "double" fare-registers comprising a register-back provided with a pair of pivot-studs one above the other and a pair of stops, a pair of main levers pivoted at their inner ends on the upper pivot-stud and having outer ends adapted to connect with the actuators of the respective registering mechanisms and bell mechanisms of the double register, a spring holding said levers normally against said stops, a pair of links pivoted to said levers, depending therefrom, and having thickened and slotted lower ends, and interchangeable removable levers adapted to be pivoted on the lower pivot-stud of said register-back and having in common stud-pins to coact with said slotted lower ends of said links and means for connecting the removable lever with a ringing device. 75

2. The combination, in double-register-operating devices, of a register-back provided with a pair of pivot-studs one above the other and a pair of stops, a pair of main levers pivoted on the upper pivot-stud and adapted to 90 connect with the actuators of the respective registering mechanisms and bell mechanisms of the double register and constructed with rigid arms at top, a spiral spring stretched between said rigid arms and operating to hold 95 said levers normally against said stops, a pair of links pivoted at their upper ends to said levers and having slotted lower ends, and a substantially-T-shaped lever or levers pivoted on the lower stud of said register-back 100 and having studs on its lateral arms to coact with the said slotted ends of said links.

3. The combination, in double-register-operating devices, of a register-back having a pair of studs one above the other, a pair of main levers pivoted on the upper pivot-stud and adapted to connect with the actuators of the respective registering mechanisms and bell mechanisms of the double register, a pair of links pivoted to said levers, depending 105 therefrom and having thickened and slotted lower ends, and a pair of substantially-T-shaped levers pivoted on the lower pivot-stud of said register-back and having short stud-pins to coact with said slotted lower ends from 110 front and back respectively, substantially as hereinbefore specified. 115
